DESIGN FOR A VELOCIPED

Herman L. Kraeft, Cleveland Heights, Ohio, assignor to The Murray Ohio Manufacturing Company, Cleveland, Ohio, a corporation of Ohio

Application April 19, 1935, Serial No. 56,470

Term of patent 7 years

To whom it may concern:

Be it known that I, Herman L. Kraeft, a citizen of the United States, residing at Cleveland Heights, in the county of Cuyahoga and State of Ohio, have invented a new, original, and ornamental Design for a Velocipede, of which the following is a specification, reference being had to the accompanying drawing, forming a part thereof.

In the drawing, Figs. 1 and 2 are perspective views of a velocipede showing my new design.

I claim:—

The ornamental design for a velocipede substantially, as shown.

HERMAN L. KRAEFT.
